UNITED STATES PATENT OFFICE

1,973,803

ELEVATING APPARATUS

John A. Frauen, Norfolk, Nebr.

Application April 27, 1934, Serial No. 722,777

2 Claims. (Cl. 254—89)

The present invention relates to an elevating apparatus particularly designed for use at automobile service stations for lifting an automobile for greasing, repair work and the like.

5 An important object of the invention resides in the provision of an elevating apparatus of this nature having a frame which is tiltable.

Another important object of the invention resides in the provision of a safety attachment 10 for the elevating apparatus to hold the same in elevated position.

A still further very important object of the invention resides in the provision of an elevating apparatus of this nature which is comparatively 15 simple in its construction, easy to manipulate, thoroughly efficient and reliable in use and otherwise well adapted to the purpose for which it is designed.

With the above and numerous other objects in 20 view as will appear as the description proceeds, the invention consists in certain novel features of construction, and in the combination and arrangement of parts as will hereinafter be more fully described and claimed.

25 In the drawings:

Figure 1 is a side elevation of an apparatus embodying the features of my invention showing the same in lowered position.

Figure 2 is a similar view showing the same 30 in raised position with the frame tilted.

Figure 3 is a top plan view of the frame.

Figure 4 is a top plan view of the turnable plate.

Figure 5 is another side elevation of the apparatus showing the frame in a different position 35 from that shown in Figure 2.

Figure 6 is a sectional view taken substantially on the line 6—6 of Figure 3.

Figure 7 is a bottom plan view of the central 40 portion of the frame.

Figure 8 is a vertical section through the pneumatic jack.

Figure 9 is a sectional elevational view showing the top of the pneumatic jack in elevation with 45 the central portion of the frame in section.

Figure 10 is a similar view but showing the frame in horizontal position.

Referring to the drawings in detail it will be seen that the numeral 5 denotes a cylinder embedded in the ground being open at the top and closed at the bottom. A flange 6 extends outwardly from the top of the cylinder. Numeral 7 denotes a hollow piston of elongated construction slidable in the cylinder 5. The bottom of 55 the piston has a central opening 8 and an off

center opening 9. A pipe 10 is engaged in an opening in the bottom of the cylinder and rises through the opening 8. Numeral 11 denotes an air line valve control connected with the pipe 10. Numeral 12 denotes a head threaded in the upper 60 end of the piston 7 and having an outwardly directed flange 14 for resting on the flange 6 when the piston is in down position. A bolt 15 is mounted in the head 12 and rises therefrom through an opening in the center of a turnable 65 plate 16, ball bearings 17 being interposed between the plate 16 and the head 12. Across the top of the plate adjacent one side is a channel bearing 18 suitably fixed to the plate and on the other side is a rest 19.

An elongated casing 20 is embedded in the ground in spaced coextensive parallelism with the cylinder 5 and is connected with the flange 6 thereof and has slidable therein a bar 21 the upper end of which is fixed in the flange 14. This bar 70 21 has a plurality of spaced openings 22 into which a pin 23 may be projected. This forms the safety feature attachment. A stop collar 24 is fixed on the lower end of the bar to prevent the withdrawal thereof accidentally and thereby preventing the piston 7 from being elevated out of the cylinder. A little oil is used in the bottom of the cylinder. Obviously by turning on the air the piston 7 may be raised the desired height and by allowing the air to escape the piston gravitates 85 downwardly and the oil in the bottom of the cylinder acts as a check since it must flow through the relatively small opening 9 when the bottom of the piston reaches the same.

The frame used with the pneumatic jack just 90 described comprises a pair of spaced parallel coextensive bars 28. The central portions of the bars are connected by a plate 29 having openings 30 in the ends thereof. A rod 31 extends between the bars 28 below the plate 29 adjacent one 95 end. This rod 31 is adapted to be received in the channel bearing 18. Bolts 32 may be inserted through the openings 30 and threadedly engaged in openings 33 in the plate 16 when it is desired to maintain the frame in a horizontal position. 100 If it is desired to tilt the frame as shown in Figures 2 and 9 then these bolts are removed. On one end of the frame is an axle 35 with wheels 36 on the ends thereof. Chock members 37 are provided on the frame one adjacent each end. The 105 automobile is run over the frame when in a position shown in Figure 1 and when the frame is raised by the pneumatic jack it engages the axles of the car. At the end of the frame remote from the axle 35 is a cross rod 40 used similarly to the 110

rod 31 with a frame disposed in the position shown in Figure 5 when used for lifting big trucks, buses or the like.

It is thought that the construction, operation, utility and advantages of this apparatus will now be clearly understood by those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the inven-

tion as hereinafter claimed or sacrificing any of its advantages.

Having thus described my invention, what I claim as new is:

1. In a jack structure, a liftable head, a pin rising from the head, a plate having an opening to receive the pin, ball bearings interposed between the plate and the head so that the plate may be easily turned, a channel bearing on the plate, a frame, a cross rod in the frame rockable in the bearing. 80

2. A jack structure of the class described including a lifting mechanism having a head, a channel bearing across the head, an elongated frame having a cross rod at one end receivable in the bearing and wheels at the other end. 85 90

JOHN A. FRAUEN.
